(57) **CLAIM**

The ornamental design for an air filter as shown and described.

DESCRIPTION

FIG. 1 is a perspective view of a frontside for an air filter showing green filtration media in our new design.

FIG. 2 is a perspective view of a backside for the air filter showing white filtration media thereof.

FIG. 3 is a plan view of the frontside thereof.

FIG. 4 is a plan view of a side thereof; the other three sides being the mirror image thereof; and,

FIG. 5 is a plan view of the backside thereof.

The air filter is shown with a symbolic break in its length. The appearance of any portion of the article between the break lines forms no part of the claimed design.

The air filter shown with break lines in FIGS. 1 through 6 indicates that no particular length or width is claimed.

The hashed areas viewable on the frontside, and shown in FIGS. 1 and 3, are indicative of the color green.

The areas corresponding to the reverse side of the hashed area shown in FIGS. 1 and 3 are shown in FIGS. 2 and 5 without hashing indicating the color white.

All surfaces not shown form no part of the claimed design.

1 Claim, 4 Drawing Sheets
